UNITED STATES PATENT OFFICE

168,604

AIRPLANE

George S. Trimble, Jr., Towson, Md., assignor to
The Glenn L. Martin Company, Baltimore, Md.

Application August 24, 1950, Serial No. 11,921

Term of patent 14 years

(Cl. D71—1)

To all whom it may concern:

Be it known that I, George S. Trimble, Jr., a citizen of the United States, and resident of Towson, county of Baltimore, State of Maryland, have invented a new, original, and ornamental Design for an Airplane, of which the following is a specification, reference being had to the accompanying drawings, forming a part thereof.

Figure 1 is a side view of an airplane embodying my new design.

Figure 2 is a fragmentary perspective view showing the tail portion of the airplane as seen from below.

Figure 3 is a fragmentary side view of the tail assembly.

Figure 4 is a fragmentary front view of the tail assembly.

Figure 5 is a fragmentary rear view of the tail assembly;

Figure 6 is a fragmentary top plan view thereof, and

Figures 7 through 12 are cross-sectional views thereof taken along the lines 7—7 through 12—12 respectively.

The characteristic features of my design reside in the parts shown by full lines in the drawing, and particularly in the novel configuration of the elongated fairing structure and its relationship to the horizontal and vertical stabilizers wherein the forwardly extending portion of the fairing changes gradually from substan-

tially circular in section at its tip portion to a substantially semi-circular, semi-elliptical section adjacent the leading edge of the horizontal stabilizer and merging into the upper surface thereof, and wherein the rearwardly extending portion of the fairing is substantially semi-circular in section with its upper surface forming a smooth continuation of the upper surface of the stabilizer.

I claim:

The ornamental design for an airplane, substantially as shown and described.

GEORGE S. TRIMBLE, JR.
